ABSTRACT OF THE DISCLOSURE

Compounds of the formulas

wherein R_1 is NO_2 or

R_2 and R_3 are H or lower alkyl of 1 to 4 carbon atoms and

wherein R_4 is

and R_2 and R_3 are H or lower alkyl of 1-4 carbons atoms, are useful as energetic plasticizers in rocket propellants.

BACKGROUND OF THE INVENTION

This invention generally relates to organic compounds useful as plasticizers in rocket propellants and more particularly to organic compounds containing the trifluoroguanyl group and to a method of preparation thereof.

Nitrocellulose containing rocket propellants have found extensive use in the prior art but in almost all cases it has been desirable to add a plasticizer to such propellants to improve their mechanical properties. It is desirable that these plasticizers be highly energetic and, if possible, also contribute in other ways to upgrading the propellant. There has long been a search for highly energetic plasticizers which would also increase specific impulse as well as burning rate and simultaneously would decrease radar attenuation of rocket propellants.

SUMMARY OF THE INVENTION

Accordingly one object of this invention is to provide organic compounds.

Another object of the present invention is to provide organic compounds which can be used as nitrocellulose plasticizers in rocket propellants.

A further object of this invention is to provide plasticizers for rocket propellants which increase specific impulse and burning rate.

A still further object of the instant invention is to provide plasticizers for rocket propellants which decrease radar attenuation.

A still further object of this invention is to provide a process for the preparation of these organic compounds.

Yet another object of this present invention is to provide chemical intermediates which can be used to prepare the organic compound plasticizers of this invention.

These and other objects of the invention are accomplished by providing compounds of the formula

2

5 wherein R_1 is selected from the group consisting of NO_2 and

10 R_2 and R_3 vary independently and are selected from the group consisting of H and lower alkyl of 1-4 carbon atoms. These compounds are prepared by a series of chemical reactions which culminate in the conversion of 15 compounds of the formula

20 wherein R_4 is either NO_2 or

25 to the desired products.

DESCRIPTION OF THE PREFERRED EMBODIMENT

The plasticizers of the instant invention represented by the formula

30 wherein R_1 and R_2 have hereinbefore been defined can be prepared by a series of chemical reactions. The compounds wherein R_1 is NO_2 can be prepared by the following sequence of reactions:

40 50 Initially an α,β -unsaturated aldehyde of the formula $\text{R}_2 - \text{CH} = \text{CHCHO}$ where R_2 is H or lower alkyl of 1-4 carbon atoms is contacted in aqueous solution with nitroform at a temperature between 0° C. and room temperature but preferably between 0-10° C. to yield

55 This aldehyde is then converted to its bis(difluoroamino) analogue by contacting it with difluoroamino sulfonic acid at a temperature between 0° C. and room temperature. The bis(difluoroamino) compound of the formula

60 65 is converted to its trifluoroguanyl counterpart by contacting it with pyridine at a temperature between 0 and room temperature.

The compounds wherein R_1 is

are prepared by a more lengthy procedure depicted as follows:

Initially a compound of the formula

is contacted in solution with KI at about room temperature to remove one of the terminal nitro groups to yield

This product is then contacted with acid at about 0-20° C. to effect replacement of potassium with hydrogen to yield

The product thereof is then condensed in solution with an aldehyde of the formula $\text{R}_3\text{CH}=\text{CH}_2\text{CHO}$ at about room temperature to yield

This product is then contacted in solution with acetic anhydride and acid at a temperature between 0° C., and room temperature to obtain the tetraacetoxy compound

This is then converted to the corresponding tetrakis (difluoroamino) compound of the formula

by contacting in solution with $\text{F}_2\text{NSO}_3\text{H}$ at between 0° C. and room temperature. The desired amidine product of formula

was obtained by contacting in solution the tetrakis (difluoroamino) compound with pyridine at a temperature between 0° C. and room temperature.

The general nature of the invention having been set forth, the following examples are presented as specific illustrations thereof. It will be understood that the invention is not limited to these specific examples but is susceptible to various modifications that will be recognized by one of ordinary skill in the art.

$\text{N},\text{N},\text{N}'$ -trifluoro-3-methyl-4,4-trinitrobutyramidine was prepared as follows:

EXAMPLE 1
3-methyl-4,4-trinitrobutyraldehyde

To a cold (0-5° C.) stirred solution of 12.5 g. (0.179 mole) of crotonaldehyde in 160 ml. of water, was added dropwise over a 1.5 hour period 27 g. (0.180 mole) of nitroform in 60 ml. of water. The reaction mixture was stirred at ambient temperature for 24 hours. The aqueous phase was extracted with four 25 ml. portions of methylene chloride, and this solution was washed with three 100 ml. portions of 5% aqueous sodium bicarbonate solution followed by three 100 ml. portions of water. The organic phase was dried with anhydrous magnesium sulfate, filtered, and the methylene chloride removed at 15 mm. leaving 24.76 g. of a clear yellow oil. Purification by distillation gave a clear, colorless oil, B.P. 85-87° C. at 0.45 mm.; n_{D}^{25} 1.4675. The structure was confirmed by IR and NMR spectra.

EXAMPLE 2
1,1-bis(difluoroamino)-3-methyl-4,4-trinitrobutane

To a cooled (10-15° C.) stirred mixture of difluorominoic acid (0.17 mole) in 20 ml. of 100% sulfuric acid and 25 ml. of fluorotrichloromethane, was added dropwise 9.85 g. (0.045 mole) of 3-methyl-4,4-trinitrobutyraldehyde in 20 ml. of fluorotrichloromethane. The reaction mixture was stirred at ambient temperature for 15 hours. The organic phase was separated from the acid and washed with four 75 ml. portions of a 5% aqueous solution of sodium bicarbonate and four 75 ml. portions of water. The organic phase was dried with anhydrous magnesium sulfate, filtered and the fluorotrichloromethane removed at 15 mm. leaving 11.71 g. of a clear, yellow oil. The desired product was distilled at 44° C. at 0.01 mm. pressure, n_{D}^{24} 1.4367. The structure was confirmed by IR and NMR spectra.

EXAMPLE 3
 $\text{N},\text{N},\text{N}'$ -trifluoro-3-methyl-4,4-trinitrobutyramidine

A solution of 4.6 g. (0.015 mole) of 1,1-bis(difluoroamino)-3-methyl-4,4-trinitrobutane in 130 ml. of ethylene chloride was cooled to 0-5° C. and to the stirred solution was added dropwise, over 30 minutes, a solution of 0.40 g. (0.005 mole) of pyridine in 15 ml. of methylene chloride. The reaction mixture was stirred at ambient temperature for 18 hours, then washed with two 50 ml. portions of 5% sodium bicarbonate solution and 50 ml. of water. The organic phase was dried over magnesium sulfate, filtered, and evaporated in vacuo at 25° C. leaving 3.14 g. of a yellow oil. The oil was distilled and the desired product was collected at 60° C., 0.20 mm. pressure; n_{D}^{22} 1.4482. IR and NMR spectra confirmed the structure.

$\text{N},\text{N},\text{N}',\text{N}'',\text{N}'',\text{N}'''$ -hexafluoro-4,4-dinitropimelamidine is prepared by the following sequence of reactions.

group consisting of H and lower alkyl of 1-4 carbon atoms.

2. A compound according to claim 1 wherein R₂ is selected from the group consisting of H and CH₃ and R₃ is selected from the group consisting of H and CH₃. 5

3. A compound according to claim 2 wherein R₁ is NO₂ and R₂ is CH₃.

4. A compound according to claim 2 wherein R₁ is

and both R₂ and R₃ are H.

5. Compounds of the formula

wherein R₂ is selected from the group consisting of H 20 and lower alkyl of 1-4 carbon atoms, R₄ is

and R₃ is selected from the group consisting of H and lower alkyl of 1-4 carbon atoms.

6. The compounds of claim 5 wherein R₂ is selected from the group consisting of H and CH₃ and R₃ is selected from the group consisting of H and CH₃.

7. The compound of claim 6 wherein both R₂ and R₃ are H.
